Thos. L. Sprague.

UNITED STATES PATENT OFFICE.

JOSEPH B. DUTTON, OF DETROIT, MICHIGAN.

GRAIN-METER.

SPECIFICATION forming part of Letters Patent No. 367,096, dated July 26, 1887.

Application filed March 10, 1887. Serial No. 230,322. (No model.)

To all whom it may concern:

Be it known that I, JOSEPH B. DUTTON, of Detroit, in the county of Wayne and State of Michigan, have invented new and useful improvements in Grain-Meters; and I do hereby declare that the following is a full, clear, and exact description thereof, reference being had to the accompanying drawings, which form a part of this specification.

10 This invention relates to certain new and useful improvements in grain-meters.

The object of the invention is to construct a device for the purpose of weighing or measuring grain, that will be thoroughly automatic 15 in its operation.

The invention consists in the peculiar construction and arrangement of the mechanism for operating the doors at the receiving and discharge ends of the grain-receptacle, in the 20 peculiar construction of the mechanism for locking the discharge-doors, and in the peculiar construction, arrangement, and combinations of the various parts, all as more fully hereinafter set forth.

25 Figure 1 is a perspective view of my improved device in position to receive grain from any suitable hopper above. Fig. 2 is a similar view showing position of parts upon discharging from the bottom. Fig. 3 is a rear 30 elevation. Fig. 4 is a central vertical section.

In the accompanying drawings, which form a part of this specification, A represents a suitable frame-work, which supports the operating parts of the device.

35 B is a bifurcated lever, the two arms of the fork of which are fulcrumed in proper bearings, a, on the frame A, the short arms of such forks supporting the receptacle C, as is ordinary in devices of this character. The end of 40 the arm b of the lever B has a vertical movement in the slotted end c of the standard D, which forms a part of the frame. This arm of the lever is provided with a weight, B', adjustable thereon, to govern the quantity, in 45 weight or measure, the receptacle C shall receive before discharging same.

E is a hopper rigidly secured to and pendent from the top girts of the frame, the lower end of such hopper projecting into the mouth 50 of the receptacle C. In this hopper E are the doors or gates F, which are secured upon rock-

shafts G, properly journaled in or through the walls of the hopper, the corresponding ends of such shafts projecting to and beyond the rear wall of the receptacle C, and have secured 55 to them the rocker-arms H, the ends of the latter being connected by means of the rods I to the upper end of the slide-bar J, which has a vertical sliding movement in guides d upon the rear end of the receptacle.

K are doors pivotably hung at the discharge or bottom of the receptacle C, as at e, and these doors are connected by means of the rods or links L to the slide-bar J.

M are counter-weights, which are secured 65 upon the doors K by means of the rods N.

O is an arm projecting inwardly from the frame, and has pivotally secured to its free end a slotted bar, P.

R is a latch-lever, which is properly fulcrumed to one of the doors K, the hook end of such lever engaging with a stop, h, on the opposite door. The longer arm of this latch-lever R should preferably be bifurcated, to embrace the slotted end of the bar P, and is retained 70 in its relative position therewith by a pin, i, which passes through the slot.

S is a spring, which bears down upon the lever R, to prevent an accidental opening of the doors K.

80 Any suitable registering mechanism may be attached to the device to designate the number of times the receptacle has been filled and discharged.

In practice, the parts being constructed substantially as described, and being in the position shown in Figs. 1 and 3, the operation is as follows: As the receptacle fills from a source of supply above the hopper, the weight of grain required overbalances the weight B' and said receptacle. In so descending the doors or gates F of the hopper are by the connections described compelled to assume a closed position against the further ingress of grain and before the receptacle has descended far enough to 85 open the discharge. In the further descent of the receptacle, the lever R is caused to slide downward in the slotted end of the bar P, and the latch of the lever is disengaged from its stop h, thus releasing the doors, which open 90 under the weight of the grain, which latter is discharged below. The grain having been dis-

charged, the weight B' compels the receptacle C to assume its original or elevated position, while the weights M close the doors of the discharge.

5 It will be seen that the doors K must move simultaneously in opening and closing, such movements being controlled by the slide-bars J, rods I, and the counter-weights, and, having been closed, the latch-lever is compelled 10 to engage with the stop h through the action of the spring S. As the slide J and receptacle ascend, the gates F are again opened through the connections described, whereupon grain again enters the receptacle, and the operation 15 is repeated, as before, until the supply has been exhausted or shut off.

A device constructed as herein shown and described will be found to be perfectly automatic in its operation.

20 What I claim as my invention is—

1. A grain-meter provided with a counterpoised receptacle, counterweighted doors at the discharge of such receptacle, and the means, substantially as described, for opening and 25 closing said doors, in combination with a vertically-moving latch-lever connected with a pivoted arm connected with the frame, substantially as and for the purposes described.

2. In a grain-meter, the combination of a 30 counterpoised receptacle, C, provided with counterweighted doors K, and a hopper provided with shut-off gates with the sliding bar J and connecting rod or link L and rods I,

and rock-shafts connected with said gates and rods, substantially as set forth.

3. The combination of a counterpoised receptacle, C, a fixed hopper, E, provided with gates F, and rock-shafts G, journaled in said hopper, with the sliding bar J, sliding in guides on the end of said receptacle, and rods I, connected to the rock-shafts of said gates F, substantially as described.

4. The combination of a counterpoised receptacle, C, provided with discharge-doors K, with the rigid arm O, bar P, pivoted thereto, 45 and a vertically-moving latch-lever, R, connected with said bar, substantially as and for the purposes specified.

5. In combination with the doors K of a grain-meter, the latch-lever R, spring S, slot- 50 ted bar P, and rigid arm O, the parts being constructed, arranged, and operating substantially in the manner and for the purposes specified.

6. In a grain-meter, the combination of the 55 counterpoised receptacle C, counterweighted doors K, rods L, vertically-sliding bar J, rods I, connected to the rocker-arms H of the rock-shafts G, gates F, and fixed hopper E, the parts being constructed, arranged, and operating 60 substantially in the manner and for the purposes described.

JOSEPH B. DUTTON.
